UNITED STATES PATENT OFFICE

DAVID B. SCOTT, OF SHINGLE SPRINGS, CALIFORNIA.

METALLIC FENCE-POST.

SPECIFICATION forming part of Letters Patent No. 289,149, dated November 27, 1883.

Application filed June 26, 1883. (No model.)

To all whom it may concern:

Be it known that I, DAVID B. SCOTT, of Shingle Springs, county of El Dorado, State of California, have invented an Improvement in 5 Metallic Fence-Posts; and I hereby declare the following to be a full, clear, and exact description thereof.

My invention relates to a new and useful metallic fence-post; and it consists, in connection with the upper portion of the post, (preferably of angle-iron,) of an improved screw-point and means for anchoring the post, as I shall fully describe, reference being made to the accompanying drawings, in which—

15 Figure 1 is a view of my post shown in the ground. Fig. 2 is a plan of the same. Fig. 3 is a vertical section of the casting A.

As a substitute for wooden fence-posts, it is claimed by many that the angle-iron fence-post comes nearest the requirements of 20 strength, durability, and economy. I have therefore illustrated my improvements in connection with this class of posts, though I do not confine myself to such posts, as the advantages and results of my invention will follow 25 its connection with other forms of posts.

Angle-iron, tubular, and other fence-posts are usually beveled or tapered at their lower ends and driven into the ground. I have found 30 that they will not hold in either hard or soft soils against the upward strain of the wires when drawn to a proper tension to fasten them, and this is the case especially where the face of the country is rolling, hilly, or cut up 35 by deep ravines which have to be crossed. In such ground, if driven when the earth is dry, they may hold for a time; but when it becomes soft in wet weather the strain of the wires, which did not move them when placed, 40 will have a tendency to draw them from the ground, as their shape and smooth surface is not such as to resist the lifting force. This more especially applies to the climatic changes on the Pacific coast, where the ground is baked 45 by the summer heat and softened by the incessant winter rains.

The object of my invention is to provide means for resisting or counteracting the upward strain of the wires in any kind of soil 50 and at all times.

A is a casting having an oblong flange, *a*, near its upper end. Into the top of this casting while still soft the angle-iron post B is inserted, the upper portion, *a'*, of the casting surrounding it, and forming, with the flange *a*, a base for it. The lower portion of the casting is made cylindrical and hollow, and is provided with a thread, *c*, upon a tapering stem or body. The lower end of this thread is formed into the point for centering in advance of the screw. There are two peculiarities of this thread. The first is that it is horizontal on the upper side and angling or inclined upon the lower side. This makes it take firmer hold on the ground than if it were an ordinary thread. The other is that the width of the thread itself is not equal throughout its length—that is, it does not project from the body or shaft an equal distance at all points. It is increased in width as it nears the point, 70 as shown. The advantage of this is that, as the holding resistance of the ground is greater in the more compact earth below, the wider thread gives a better hold, while it does not affect the entering capacity of the screw 75 through the more yielding surface or top soil. The thread, being angling on its lower side, permits the ready advancement into the ground, while its horizontal upper surface resists the vertical strain.

In placing these posts I use a pointed bar as a starter. The post is then screwed down by means of a cross-bar, suitably attached, until the oblong flange *a* rests on the ground in such position that its longer direction lies at 85 right angles to the line of the fence. On level ground, where there is no tendency to an upward strain, this would be sufficient, but on uneven ground I prefer to use, in addition, the anchor-bars D. These have their upper ends, 90 *d*, bent at right angles, and are driven into the ground obliquely until their bent ends *d* rest upon the flange *a*, or upon ribs thereon. I may use two or four of these anchor-bars, as necessity requires.

95 E are the wires, secured in a suitable manner.

The flange *a*, when thus anchored, not only assists in confining the post in the ground, but, as it projects at right angles to the line of 100

the fence, it acts as a foot-brace when high winds prevail in the rainy season, when the ground becomes soft and saturated with water.

The post thus constructed is of great utility, 5 and will be immovable against all the strain the wires will bear in hard, soft, or uneven ground.

I am aware that a fence-post having a screw-point has been heretofore known; but its construction is different from mine.

I do not claim the screw-point, broadly; but What I claim as new, and desire to secure by Letters Patent, is—

1. The post B, in combination with the casting A, forming its tapering point, said casting being provided with a thread, c, horizontal on its upper side and angled or inclined upon its lower side, and having a gradually-

increasing width to its point, substantially as herein described.

2. The post B, in combination with the casting A, forming its tapering point, said casting being provided with a thread, c, horizontal on its upper side and angled or inclined on its lower side, and increasing in width to its point, and having the right-angled flange a and socket a', and the anchor-bars D, having bent ends or heads d, engaging with the flange a, substantially as herein shown and described.

In witness whereof I have hereunto set my hand.

DAVID B. SCOTT.
